AIR SAMPLER

Howard C. Eberline, Santa Fe, N. Mex., assignor to
Eberline Instrument Corporation, Santa Fe, N. Mex.

Filed June 18, 1962, Ser. No. 70,599

Term of patent 14 years

(Cl. D16—2)

FIG. 1 is a perspective of an air sampler embodying my design;

FIG. 2, a top plan view; and

FIG. 3, an enlarged fragmentary perspective of the sampler head.

The randomly spaced perforations on the upper portion of the base member in FIGS. 1 and 2 are understood to be continuous throughout said portion.

The underside of the base is flat with three equally spaced identical casters mounted thereon.

I claim:

The ornamental design for an air sampler, as shown and described.
